UNITED STATES PATENT OFFICE.

CHARLES T. INMAN, OF AKRON, OHIO.

WALL-TIE.

SPECIFICATION forming part of Letters Patent No. 700,932, dated May 27, 1902.

Application filed September 3, 1901. Serial No. 74,193. (No model.)

To all whom it may concern:

Be it known that I, CHARLES T. INMAN, a citizen of the United States, residing at Akron, in the county of Summit and State of Ohio, 5 have invented a certain new and useful Improvement in Wall-Ties, of which the following is a specification.

My invention has relation to improvements in ties or binders for walls, either when it is 10 desired to place a pressed-brick veneer on a wall of common brick or on a wood framework, with board sheathing or thin flagging veneer on a brick or stone wall, and it is especially designed for strengthening hollow brick walls.

15 The object of my invention is to provide a cheap, compact, and durable binder or tie that will firmly bind the wall and that will be readily applied.

My invention consists in the peculiar and 20 novel tie or binder hereinafter described and then specifically pointed out in the claims, reference being had to the accompanying drawing, which forms a part of this specification.

25 The accompanying drawing represents a portion of a wall composed of three bricks 1, 2, and 3, on which is laid my improved binder

4. This binder is composed of a number of wires (preferably three) braided into a loose 30 flat plait 4. As the wall is built this plait is laid in the mortar extending across the bricks nearly to the outer face of the side brick and

held by the next superimposed brick. When a hollow wall is needed, a space is left where the brick 2 is the binder extending across this 35 space. Where it is desired to use this binder to connect a brick veneer with a wood house, one end of the plait is bent up at a right angle and nailed to the sheathing, a construction that will be readily understood without 40 an additional figure.

Where pressed brick are used and the structure of mortar is thin, the binder is previous to being used run between rolls and flattened.

45 I claim as my invention—

1. A wall-tie consisting of a plurality of interlocking wires in the form of a loose braid with the interstices between the wires of sufficient size to permit the entrance therein of 50 cement or similar substances, substantially as shown and described.

2. An improved wall-tie consisting of a number, preferably three wires, braided into a loose plait, and flattened between rolls, substantially as shown and described.

55 In testimony that I claim the above I hereunto set my hand in the presence of two subscribing witnesses.

CHARLES T. INMAN.

In presence of—

C. P. HUMPHREY,
C. E. HUMPHREY.
